(57) **CLAIM**

The ornamental design for an electronic cymbal, as shown and described.

DESCRIPTION

FIG. 1 is a top view of the electronic cymbal according to the claimed design;

FIG. 2 is a bottom view of the electronic cymbal according to the claimed design;

FIG. 3 is a front view of the electronic cymbal according to the claimed design;

FIG. 4 is a rear view of the electronic cymbal according to the claimed design;

FIG. 5 is a left-side surface view of the electronic cymbal according to the claimed design;

FIG. 6 is a right-side view of the electronic cymbal according to the claimed design; and,

FIG. 7 is a perspective view of the electronic cymbal according to the claimed design.

The ornamental design which is claimed is shown in solid lines in the drawings. The broken lines in the drawings are for illustrative purposes only and form no part of the claimed design.
